(57) **CLAIM**

The ornamental design for a wastebasket, as shown and described.

DESCRIPTION

FIG. 1 is a top perspective view of a wastebasket.

FIG. 2 is a bottom perspective view of the wastebasket.

FIG. 3 is a front side view of the wastebasket, the back side being a mirror image of the front.

FIG. 4 is a right side view of the wastebasket, the left side being a mirror image of the right.

FIG. 5 is a top view of the wastebasket; and,

FIG. 6 is a bottom view of the wastebasket.

The dot-dash broken lines in the drawings depict portions of the wastebasket which form no part of the claimed design. The evenly spaced broken lines depict portions of the wastebasket which form no part of the claimed design. The wastebasket is shown with symbolic breaks in its length. The appearance of any portion of the article between the break lines form no part of the claimed design.

The dot-dash broken line in FIGS. 1 & 5 depict the boundary of the claim that forms no part of the claim design.

1 Claim, 6 Drawing Sheets
